UNITED STATES PATENT OFFICE.

HERBERT McNULTA, OF CHICAGO, ILLINOIS.

PASSENGER-CAR FOR RAILWAYS.

1,228,797.

Specification of Letters Patent. Patented June 5, 1917.

Original application filed June 28, 1909, Serial No. 504,651. Divided and this application filed August 12, 1912. Serial No. 715,138.

To all whom it may concern:

Be it known that I, HERBERT McNULTA, a citizen of the United States, and resident of Chicago, in the county of Cook and State of Illinois, have invented certain new and useful Improvements in Passenger-Cars for Railways, of which the following is a full, clear, and exact specification.

This invention relates to improvements in passenger cars for railways, more particularly to that type commonly known as trolley or street cars, and especially to stepless side entrance cars, that is to say in which there is but one low step from the ground or street to the platform of a side or center entrance car described in application Serial No. 504,651, filed June 28, 1909, and now Letters Patent No. 1,035,216, granted me August 18, 1912, of which this is a divisional application.

One of the objects of my present invention is to provide means by which all passengers entering and passing from a stepless car are at all times directly in front of and in close proximity to the conductor when standing in a position convenient for receiving fares and for carrying out his duties in connection with the operation of the car, and whereby the motorman or driver of the car is entirely relieved of any responsibility for or interference by such passengers.

Another and important object of my invention is a stepless car, the entrances and exits of which are so arranged as to provide for a substantial increase in the number of seats in a car of given length, as compared with end platform cars.

Another important object of my invention is an arrangement of entrances and exits of a passenger car providing for floor spaces to be occupied by standing passengers, near the entrances and exits, and thereby readily available to them.

A further object of my invention is to provide a novel arrangement of gates or doors at the entrance and exit of the car platform, so that the side of the platform may be closed or opened, and so that on a center platform car either side of the car may be open and the other side closed by one set of doors or gates shifted by the conductor without leaving the platform.

A still further object of my invention is to provide in a passenger car having either end or center platforms and having separate entrances and exit passages for passengers, doors or gates to the compartments of the car, novel in construction and operation within convenient reach of the conductor from the position he will usually occupy when the car is in operation, and which can be easily manipulated by passengers entering or leaving the compartments; the novel arrangement of these doors being such as to permit the construction of the platforms of end or center platform cars with platform center or intermediate sills or supports substantially integral with or continuations of the center or intermediate sills of the car body, and clear of the truck wheels and motors when such truck wheels or motors are located so closely to the platform that they will barely clear the outside platform sills or knees.

With these ends in view, my invention finds embodiment in certain features of novelty in the construction, combination and arrangement of parts by which the said objects and certain other objects hereinafter appearing are obtained: as fully described with reference to the accompanying drawings and more particularly pointed out in the claims.

In said drawings:

Figure 1 illustrates in side elevation a trolley car embodying a part of my invention.

Fig. 2 is a plan view in horizontal section on lines *a*—*b* of Fig. 1.

Fig. 3 is a vertical cross section of the same car on line *c*—*d* of Fig. 1.

Fig. 4 is a plan of the platform of the car shown in Fig. 1, showing the central portion of Fig. 2 on an enlarged scale and in more details.

Figs. 5, 6 and 7 are plan views in horizontal section through the doors of several arrangements of non-reversible doors between the platform and the compartment of a car.

Fig. 8 is a plan view in horizontal section of an arrangement of reversible compartment doors, being a modification of the arrangement shown in Figs. 3 and 4.

Fig. 9 is a plan view in horizontal section

of the compartment doors shown in Fig. 8, and illustrates the position of parts during the operation of reversing the doors.

In passenger cars as constructed prior to my invention as described in my Patent No. 1,035,216, before referred to, the floor of the platform has been at such height that one or more exterior steps have been constructed by which the passenger mounts to the floor or platform from the ground or track level, street cars requiring one or more steps, so called inter-urban and steam railway passenger cars requiring two or more steps.

In practice these steps are of greater individual rise than is common in ordinary stairways, so that the exertion required of the passenger is greater than if the same height were reached by steps of less individual rise. Also the larger the individual rise and the larger the number of steps in continuous flight the greater the exertion required and the time consumed by the passenger in making a safe and secure entrance to or exit from the car.

To reduce the exertion and time required by the passenger to enter or to leave the car, and to make the entrance and exit more safe and secure, a part of my invention is embodied in a stepless car having a portion of its floor or its platform lowered to or constructed at a level that it may be mounted directly from the ground by the passenger taking one step, such floor or platform extending across the car preferably from sill to sill, and communicating with the main floor of the car located over the trucks and wheels by means of an inclined plane or of but few steps of convenient, and preferably of easy rise and tread, said steps being at a substantial distance from the point of entrance to the platform.

In the accompanying drawings in which like figures indicate like parts a portion of the floor or the platform 21 is located at a height from the ground or from the top of the rail 22 that it may be mounted by the passenger taking one step, and extends across the car from outside sill 23 to outside sill 24, its length longitudinally of the car being such as may be desired within the limits imposed by clearance for the trucks 25.

Steps or stairs 26, 27 lead from the platform 21 to the main floor 28 of the seating compartment, which floor although shown horizontal may be inclined when for any purpose or style of trucks this may be desirable. In Figs. 1, 2 and 3 a car is illustrated having an entrance passage 29 continuous with the platform 21 but separated from the exit passages 30, 30 by the vertical posts 31, 31 and the hand rails 32, 32 attached to posts 31, 31. The passenger boards the car at passage 29, passes across the plat-

form 21 in view of the conductor facing him at 33, behind the railing 34, mounts the steps 26 and enters the compartment 28 through the door 35. The passenger when leaving the car passes from the compartment 28 through the door 36 down the steps 27 through the exit passages 30, at the level of the platform 21, and to the ground with a single step of the foot. The doors 35 and 36 may be located respectively at the top or bottom of the steps 26 and 27.

The rise of steps in dwellings and in other buildings seldom exceeds eight inches, whereas the rise of steps in passenger cars is seldom as small as eight inches, and in some cases exceeds thirteen inches, the larger rise being used on cars for reducing the number of steps required to reach the floor of the car from the ground so as to occupy the least amount of horizontal space and give width to the platform.

With the construction embodied in my invention of interior steps from the platform 21 to the main floor of compartment 28, the number of steps may be increased, and therefore their individual rise reduced, to reach the compartment floor 28 from the ground 22 over that in the usual construction, and the width of the platform retained to extend from sill to sill, because the platform 21 is below the interior steps 26 and 27.

It is obvious that my construction shown in the drawings as applied to a side or center entrance car may be used on end platform cars, the platform 21 extending from outside platform sill to outside platform sill across the car and steps 26 and 27 arranged for entering and leaving the compartment 28, but I have preferred to show my invention applied to side or center entrance cars since this and other features embodied in my invention are especially adapted to a side or center entrance car, and that furthermore some of these features are impossible without or in the absence of side or center entrances.

I am aware that passenger cars have been constructed with end platforms having separate entrance and exit passages on each platform from the ground to the platform and between the platform and the compartment of the car, and that side or center entrance cars have been constructed with separate entrance and exit passages from the ground to the platform, but I do not know of any stepless side or center entrance car having been constructed with separate entrance and exit passages from the ground to the platform on either, or both sides, of the car and having at the same time separate entrance and exit passages from the platform to the compartments of the car.

My invention herein described of a stepless platform or floor with the platform ex-

tending the full width of the car at its sills enables a side or center entrance car to have for the first time separate entrance and exit passages from the ground to the platform on either or both sides of the car, and at the same time separate entrance and exit passages to the compartments from a platform extending the full width of the car.

In Figs. 1, 2 and 4 entrance passage 29 and exit passages 30, 30, separated by the vertical post 31, and the hand rails 32, are shown at one side of the platform 21 with doors 56 and 57 inclosing the other side of the platform, so that passengers may enter and leave at but one side of the car; and there are shown also steps 26 and doors 35 separate from steps 27 and doors 36 connecting the platform 21 to the compartments 28. By removing the platform inclosing doors 56 and 57, both sides of the car will be open for the ingress and egress of passengers. It is customary, however, to have but one side of a car open for the ingress and egress of passengers, and with my arrangement either side of the car at will may be open without having duplicate devices and having separate entrance passages 29 and exit passages 30, 30 to the platform 21, and separate entrance doors 35 and exit doors 26 between the platform 21 and the compartments 28, and the other side closed.

Figs. 1 and 2 show the right side of the platform 21 open and the left side closed by the doors 56, 57, the direction of operation 35 of the car being to the right hand in the drawings as shown by the position of the trolley pole 87 in Fig. 1. By shifting the position of the doors 56 and 57 from the left hand to the right hand side, by means 40 hereinafter disclosed, and by shifting the hand rails 32, separating the entrance passage from the exit passages, from the right hand side of the platform 21 to the left hand side in similar but reversed position, and 45 connecting the post 31 to the guards 69 on the left hand side, the arrangement of the entrance and exit passages is reversed from that shown in the drawings.

Furthermore, in passenger cars as heretofore constructed it has not been possible to construct the side framing in the form of a truss of which the diagonal members extended above the level of the window rails or sills without such diagonal members crossing the windows and annoyingly obstructing the view of the passengers.

Passenger cars, commonly known as side or center entrance cars by reason of the entrances being located between the trucks and 30 at some distance from the ends of the car, but not necessarily at the exact center, have been constructed with two or more steps between the ground and the car platform, this construction necessitating the cutting away of

the sills, if of wood, or of their being bent in 65 a horizontal or vertical plane reinforced if of metal, in either case requiring additional material either in the side sills or in intermediate or center sills to obtain the requisite strength.

Again, these side entrance cars have had platforms and outside steps so short longitudinally of the car that diagonal truss members above the window rails or sills, would pass across so many windows as to 75 annoyingly obstruct the view of a large number of passengers.

My invention, however, embodies an arrangement of parts by which a side or center entrance car may be constructed with the 80 side framing of wood or metal in the form of a truss whose diagonal members may pass above the line of window rails or sills, in some cases without being located across the windows in the side of the car, and not 85 crossing more than two windows at each side of the entrance as shown in Fig. 1; this construction being made possible by reason of the low platform or floor 21 which may extend so close to the trucks 25 that few, if 90 any, of the windows opening above the main floor 28 will be crossed by diagonal truss members, and that the diagonal truss members will pass above the tops of any window openings located over the platform or 95 floor 21.

In Fig. 1 it will be seen that by reason of the platform 21 being located below the level of the main floor 28, the sills 23 are bent or 100 built up so that the portion 37 lies at or below the level of the platform 21, and below the portion 38 of the sills 23 which extend over the trucks 25: the portions 39 of the sills 23 being formed of separate pieces or by bends in the sills 23. The portions 39 are 105 extended at 40, and with the portions 37 and 40 form the lower chord of a truss suspended over the truck centers 41, through the posts 42, the car body bolsters 43, the other members of the truss being the platform corner 110 post 44, the window posts 45, the window rails 46, extensions 47 of the portions 38 of the sills 23, the girths 48, the lintel 49 of the side doors, such lintel being extended if necessary, of the diagonal struts or compression members 50, 50, and of each other members as may be necessary or desirable.

The struts or compression members 50 are extended to 51 and joined to the portion 38 of sills 23 to support the overhang of the car beyond the body bolster 43, the posts 52 and the diagonal members 53 (see Fig. 1) being used to strengthen the overhang. In Fig. 1 the diagonal members 50 cross the window openings 54, but the view of passengers through these windows will not be annoyingly obstructed because, as will be seen in Fig. 2, the seats 55 are arranged longitudi-

nally so that the backs of passengers seated thereon will be toward the windows 54, 54. When, however, the floor or compartment 28 extends a shorter distance from the body 5 bolster 43 toward the platform 21 than in the car shown in Figs. 1 and 2, the diagonal members 50 may pass clear of the window openings 54, 54, the shortening of the length of the compartment 28, or the location of 10 the trucks 25 farther toward the ends of the car, provides for lengthening the platform 21, and for seats thereon if desired.

Since the center platform 21, with one entrance passage 29 and two exit passages 30, 15 30 occupies less longitudinal space in the car than would two end platforms each having one entrance passage and one exit passage of the same length longitudinally of the car as on the center platform, and since in a center platform car the space corresponding to that occupied on one of the end platforms of a car by the motorman may be utilized for seats, the seating capacity of a center platform car is greater than that of an end 25 platform car of like over all dimensions.

In addition, the center platform car with longitudinal seats arranged near the entrances and seats, as shown at 55, 55 (see Figs. 2 and 4) has the advantage, as compared with an end platform car, having longitudinal seats arranged near the platforms, that the open standing spaces between the longitudinal seats 55, 55 are located in close proximity to both of the entrances and to both of the exits of the compartment and of the car, whereas on an end platform car only one of these spaces is in close proximity to the rear platform, which is commonly used as the only entering point 40 to the car; with the result that these standing spaces may be more easily occupied by passengers than on end platform cars in which entering passengers traverse nearly the entire length of the compartment to 45 reach the forward standing space, which they are loath to do when the car is crowded because of the difficulty of reaching the forward standing space.

In passenger cars as heretofore constructed, of that type having doors or gates inclosing the sides of the car platform, a set of doors or gates is provided at each edge of the platform, which are hinged to the posts and to one another for folding into a space of small compass, or which are slid longitudinally inside or outside of the side of the compartment of the car, for the purpose of opening the sides of the platform for the ingress or egress of passengers. Such 50 hinged or folding doors interfere more or less with passengers, and such sliding doors necessitate such construction in the side framing of the car, and occupy so much space inside or outside of it that the clear 55 inside width of the car is reduced so that

the seats located therein are crowded nearer together than would be the case were such sliding doors not in use.

A novel arrangement of the side inclosing doors or gates for a car platform is embodied in my invention, consisting of doors or gates, sliding or folding together if necessary to clear obstacles that may obstruct their passage across the platform, and of means for transferring them across the platform consisting of overhead rails extending from side to side of the car over the platform, on which slides or wheels carry the doors or gates. By this arrangement the doors or gates are entirely removed from 70 that side of the platform in use by passengers, and hence do not interfere with them, and they need not be sub-divided into a large number of sections to fold into a small compass. For a car on which either one or 75 the other of its sides is to be always open and the other side closed only one set of doors or gates is required.

In Figs. 1, 2, 3 and 4 the folding doors 56 and 57 of such width when folded together 80 that they will pass the guard 69 while being swung across the platform 21, are suspended from the rollers 83, (see Fig. 3) which travel across the platform on the overhead rails 84, the rails 84 having inclined surfaces near 85 the sides of the car at 85, 85, by means of which the rollers 83 will quickly rise and lift the lower edges of the doors 56, 57 clear of the floor of the platform 21, in starting the shift of position of the doors, and will, at 90 the opposite side, lower the doors to the platform 21.

It is obvious that this arrangement for transferring the doors 56, 57 from side to side of the platform is applicable to an end 95 platform car as well as to a side or center entrance car.

Heretofore the door openings or passages have commonly been constructed between the platform and the compartment of a passenger car substantially crosswise or at right angles to the length of the car.

I am aware that single door openings have been constructed diagonally or at an oblique angle with the length of the car in the interior structure of it for the purpose of changing the direction of, or the location of, a passage from the side toward the center of the car longitudinally, or for the purpose of communicating with some interior subdivision of the compartment, but I do not know of passenger cars being constructed with two door openings or passages between the platform and the compartment set diagonally or at an oblique angle with the length 120 of the car, and converging toward the platform.

Embodied in my invention are novel arrangements of the separate entrance and exit door or gate openings and novel doors or 125

gates between the platform of a car and its compartment, applicable to end platform cars as well as to side or center entrance cars, the main feature of which is that a pair of doors or gates are located with the planes of their openings diagonal to the longitudinal vertical center plane of the car and converging toward the platform.

In the several figures of the drawings, the 10 pair of doors 35, 36, located between the platform 21 and the compartment or main floor 28, have their openings which the doors 35 and 36 normally close, extending between the post 60 (see Fig. 5) and the posts 59, or between the posts 60 (see Figs. 6 and 7) and the fixed center post 58, or between the post 60 and the center door posts 66 (shown in Figs. 2, 3, 4, 7 and 9) said posts 66 being revoluble.

20 The planes of these door openings or the planes of the doors when normally closed lie diagonally to a vertical center plane passing longitudinally through the car, and these planes converge toward the platform 21; the purpose being that with a given width of opening between the posts 60 and the posts 58, 59 or 66, the posts 60 will be farther from the outside platform corner post 44 than if the posts 58, 59 or 66 and the post 60 were set 25 in line with the post 44, and the openings thus substantially crosswise or at right angles to the longitudinal center line of the car.

30 The results are that the passenger entering or leaving the compartment 28 is directed more nearly toward the longitudinal center plane of the car and farther away from passengers seated in the seats 55 than if the door openings of equal width were located 35 in crosswise; that more space is inclosed in the compartment 28 without loss of useful space on the platform than if the openings were located crosswise; and that, in either end platform or side entrance cars in which the 40 trucks 25 (Fig. 1) are located close to the platform 21 or to the body end sill 62 (Figs. 5 and 6), center or intermediate platform sills substantially integral with or continuations of the body center or intermediate 45 sills 63 (Figs. 5 and 6) may be used to support the platform by bending them downward between the body end sill 62 and the door posts 58, 59 or 66, which platform sills could not be used integral with or continuations 50 of the body center or intermediate sill 63 in cars in which the door openings were crosswise and located over the body end sill 62 because the bend in the platform center sills 55 would interfere with the trucks or wheels 60 when the car passed around curves.

In Fig. 5 the doors 35 and 36 are shown as sliding telescopic doors operating in the usual manner to close against the post 59, so spread from the longitudinal center line of 65 the car as to form with the center post 58 a

space 58^a on the platform, in which space the conductor may be located.

In Fig. 6 another arrangement is shown in which the sliding doors 35 and 36, operating in the usual manner, close upon the center door post 58, thus bringing the doors 35 and 36 and their openings more nearly toward the center of the car, and giving greater clearance to passengers seated on the seats 55, 55 from passengers entering and 70 leaving the car than as shown in Fig. 5.

In Fig. 7 an arrangement is shown similar to that in Fig. 6, except that door 36 at the right hand of Fig. 7 is a swinging door shown as swinging outward, though if desired it may swing in either direction; and in this connection it should also be stated that all of the doors 35 and 36 may be similar swinging doors.

80 A novel arrangement of the pair of doors 35 and 36 embodying a part of my invention, is illustrated in Figs. 1, 2, 3, 4, 8 and 9, in which a sliding door 35, hung from the usual rollers 64 (Fig. 3) traveling on the usual rails 65 (Fig. 3) is carried by the vertical post 66 to which the rails 65 and its braces 67 (Fig. 3) are fixed. The vertical post 66, shown in the drawings as a channel section, carries also the swinging door 36, whose 85 hinges 68, fitted with springs for retaining 90 the door 36 normally in one position, are 95 fixed to the post 66.

The post 66 is pivoted at its top at 75 and at its bottom at 74 in suitable bearings, such as shown in Fig. 3, so as to be free to 100 turn, carrying with it the doors 35 and 36; the purpose being the use of the sliding door 35 for entering the compartment 28, from the platform 21, and of the swinging door 36 for passing from the compartment 28 to 105 the platform 21, the positions of the doors 35 and 36 relative to the platform 21 and to the compartment 28 being reversible by revolving the post 66 about its pivot 73, 74 so that whichever side of the car is open for 110 the ingress and egress of passengers, the doors 35 and 36 may be placed in proper relation thereto, which is accomplished by 115 swinging the doors 35 and 36 in the direction indicated by the arrows in the left hand portion of Fig. 4, and as indicated by the arrows in Fig. 9 until the hinged door 36 occupies the position indicated by the dotted lines in the left of Fig. 3, and the door 35 occupies the position indicated by dotted 120 lines at the left and below the center line of Fig. 4.

The sliding door 35, normally closed against one or the other outer door posts 60, on being opened slides inwardly and diagonally toward the center of the car and over the platform 21, and is provided with guards 125 69 (Figs. 3 and 4) consisting of wire screens or glazed partitions, or other suitable materials, to prevent persons on the 130

platform 21 being struck by the sliding door 35 while it is being moved to an open position.

The swinging door 36 swings closely to and may pass both the outer door posts 60, and is normally held close to one or the other of the posts 60, by the tension of its spring hinges 68 against the stop 70 (Figs. 2 and 4) or against the bottom 71 (Figs. 8 and 9) so that it may be normally opened outwardly only toward the platform 21, the post 66 is held by a hook 86, (see Fig. 3) or by any other suitable locking device in either of the two positions at which the doors 35 and 36 will normally close the openings between the posts 60 and the post 66, in the arrangement shown in Figs. 1, 2, 3 and 4.

The positions of the doors 35 and 36 are reversed by first releasing the hook 86, then partially opening door 35 clear of post 60 and pulling the door 35 outwardly toward the platform 21. The post 66 is thereby revolved until the door 35 is in the line in which it will slide into its closed position on that side of the post 66 opposite to that from which it was swung. At the beginning of this operation the door 36 will be against the stop 70 as shown in Figs. 2 and 4, and the stop 70 is permanently fixed to the post 60 so that the door 36 may be normally closed against the stop 70 to form a weather-proof joint. In order to shift the position of the door 36 from one door opening to the other by the method of operation previously described, the door 36 must pass inwardly and swing through the compartment 28.

In order that the door 36 may pass the stop 70 the pivot line of its hinges at 72 in Fig. 4 is set eccentric to the axis of the pivots 73 and 74 of the posts 66, so that as the posts 66 revolve about their pivots 73, 74, the pivot line 72 of the hinges 68 of the door 36 will be so moved that the door 36 will be withdrawn from the stop 70, and will then, by the tension of its spring hinges 68, swing around into compartment 28 toward its new position. As soon as the door 36 is clear of the stop 70 the movement of the door 35 and of the post 66 is discontinued and the door 36 is then manually drawn against the tension of its spring hinges through the opening to which it is being shifted and behind the stop 70 on the post 60 against which it will close when in its new position, and the movement of the door 35 and of the post 66 is then continued until the door 35 is in proper position to be slid into its new position covering the opening previously occupied by the door 36. The hook 86 is engaged to lock the posts 66 in its reversed position thus completing the operation of reversing the doors 35 and 36.

For the purpose of reducing the number of operations required to shift the positions 65 of the doors 35 and 36, as previously de-

scribed, and to reduce the number of guards 69 from two to one, I have shown in Figs. 8 and 9 a modified arrangement for shifting the above described positions of the doors 35 and 36, and this arrangement is the one I prefer.

The sliding door 35 and the swinging door 36 are mounted, as previously described, on the pivoted post 66, except that the door 36 has its pivot line 72 through the hinges 68 coincident with the axis of the pivots 73 and 74 of the posts 66, as shown in Figs. 8 and 9. The buttons 71, capable of being turned out of the path of movement of the door 36 and mounted on the posts 60, are substituted for the permanent stops 70 in Fig. 4, and there is but one guard 69 for the sliding door 35, this guard 69 being pivoted at 75 and carrying fixed to it a gear 76 whose center coincides with the axis of the pivot 75. The gear 76 meshes with a gear 77 fixed to the pivoted posts 66 with its axis coincident with the axis of the pivots 73 and 74 of the posts 66.

I do not limit myself to the use of the gears 76 and 77 herein described for giving a simultaneous motion in opposite directions of the guard 69 and the posts 66, as there are other means of accomplishing the same results, for example by levers, or by crossed chain belting.

The hand rails 32 (see Figs. 8 and 9) are hinged to the guards 69 by a pivot 79, and are preferably provided with a suitable latch herein shown as a tongue 87, formed at their ends and adapted to be held in jaws 88 fixed to the post 31 by pins 89 passing through a tongue 87 and the jaw 88, the function of the hand rails being to separate the entrance passages and the exit passages on the platform 21, as shown in Figs. 2 and 4.

The guard 69 is provided also with a bolt 80 sliding up and down on the outer edge of the guard 69, and fitting into the sockets 81 and 82 let into the floor of the platform 21, its purpose being to securely hold the guard 69 and, therefore, the doors 35 and 36 in one or the other of their normal positions during the operation of the car.

There are other locking devices in ordinary use which will perform the functions of the bolts 80 and the sockets 81 and 82. In the arrangement of parts as described and as shown in Fig. 8, the doors are in their normal position for operation, the sliding door 35 on the left, and the swinging door 36 on the right, the door 36 being prevented from opening inwardly by the button 71.

The entrance 29 and the exits 30 of the platform 21 are at the right of Fig. 8. To reverse this arrangement so that the entrance passage 29 and the exit passage 30 on the platform 21 may be to the left, and so that the door 35 may be on the right, and the door 36 on the left, the buttons 71 are

turned to permit the door 36 to pass them, the sliding door 35 is partly open to clear the post 60, the hand rail 32 is unfastened from the post 31 by removing the pin 89 from the jaw 88 (Fig. 3), and the bolt 80 is drawn up from the socket 81. The hand rail 32 is swung to the left on the hinge 79, the guard 69 is then swung to the left about the pivot 75, the gears 76 and 77 thereby revolving the post 66 with the attached doors 35 and 36 in a direction that the door 35 moves outwardly toward the platform 21, and when one half of the movement is completed the position will be as shown in Fig. 9 and the direction of motion as indicated by the arrows in Fig. 9.

Continuing the movement of guard 69 until the bolt 80 registers with socket 82, locking it therein, closing door 35 to the right, turning the button 71 at the left behind the door 36 now on the left of post 66, and fastening the hand rail 32 to the vertical post 31 at the left side of the platform 21, completes the reversal of the doors 35 and 36 and of the entrance and exit passages 29, 30 on the platform 21 from the right to the left side.

In Fig. 1 I have shown a car in which my invention finds embodiment, provided with a trolley pole 90; with its trolley wheel 91 in engagement with an overhead line wire 92 with its trolley rope 93 indicated as passing downwardly through the roof of a car at a point about midway its length to a point convenient for its manipulation by the conductor standing on the low platform of the car; the invention of which, however, is not herein described or claimed, and forms the subject matter of another co-pending application, Serial No. 715,137 filed August 12, 1912, also a division of said first mentioned application, Serial No. 504,651, filed June 28, 1909.

Having described my invention, what I claim and desire to secure by Letters Patent of the United States is:

1. A railway passenger car comprising in combination a car floor, a platform extending the entire width of said floor in a plane below the same, steps leading from the platform to said floor, an inside door directly fronting said steps, substantially as described.

2. A railway passenger car comprising in combination a car floor, a platform extending substantially the width of said floor, in a plane below the same, steps located toward the opposite sides of said platform, and doors at the top of said steps in diagonal arrangement with reference to the body of the car, substantially as described.

3. A railway passenger car comprising in combination a car floor, a platform at the middle of the car extending the entire width of said floor in a plane below the same, a side entrance to said platform steps leading

from the platform to said floor, and separate entrances and exits to said steps, substantially as described.

4. A railway passenger car comprising in combination a car floor, a platform at the middle of the car extending the entire width of said floor in a plane below the same, steps leading from said platform to the floor, separate entrances and exits therefor and seats arranged lengthwise of the car adjacent said entrances and exits, and thereby providing a broad space for passengers making entrance to and exit from the car floor, and for standing room, substantially as described.

5. A railway passenger car comprising in combination a car floor, a platform extending the entire width of said floor in a plane below the same, steps leading from said platform to the car floor, converging doors located at the top of said steps, and means whereby said doors when moved to an open position are suspended at a point immediately above the platform, substantially as described.

6. A railway passenger car comprising in combination a car floor, a platform at the middle of the car extending substantially the entire width of said floor in a plane below the same, a side entrance to said platform stairways leading from near the opposite sides of said platform to said floor, and hand rails and guards 69 supported from said platform whereby passengers are compelled to cross said platform to reach the car floor, and exit passengers to pass from said floor directly to the entrance side of the platform, substantially as described.

7. A railway passenger car comprising in combination a car floor, a platform extending the entire width of said floor, in a plane below the same, a side entrance to said platform exit steps adjacent the open side of said car from the floor to said platform and entrance steps at the closed side of said car leading from the platform to said floor, and means whereby passengers making their entrance to and exit from said platform are separated from each other, substantially as described.

8. A railway passenger car comprising in combination a separated car floor, a platform between said floors extending the entire width thereof and in a plane below the same, entrances at both sides of said platform exit stairways leading from said floors to said platform at an open side of the car, entrance stairways adjacent the opposite and closed side of the car leading from the platforms to said floors, whereby passengers simultaneously making their entrance and exit to both floors of the car may do so without obstructing each other, and without traversing more than half the total length of the car, substantially as described.

9. A railway passenger car comprising in

- combination a separated floor, a platform intermediate of said separated floor extending to the outer side sills of the car in a plane below the floor, means for alternately opening and closing the sides of the car adjacent the sides of said platform, exit steps respectively from the adjacent ends of said floors to the side of the platform next the open side of the car, entrance steps from the platform to the adjacent ends of said floors next the closed side of the car, oppositely arranged seats with their respective backs adjacent the side of the car, transversely arranged seats therefrom to the ends of the car, with a passage between said seats, and seats closing the ends of said passage ways and leaving an inclosed standing space between said seats and adjacent to the end of the car, substantially as described.
10. A railway passenger car comprising in combination a car floor, a platform extending the entire width of said floor in a plane below the same, means for maintaining one side of said car closed and the other open adjacent the sides of said platform, exit steps leading from the car floor to the open side of said platform, entrance steps leading from said platform to the car floor, a door at the top of the exit steps, a door at the top of the entrance steps, which said doors converge toward each other on a line substantially centrally the width of the car, whereby moving space for the doors is reduced to a minimum, the safety and non-contact of entrance and exit passengers is provided for, and means whereby passengers entering and leaving the platform are prevented from obstructing each other, substantially as described.
15. A railway passenger car the entrance and exit of which are through the sides of the car at a point substantially removed from its ends, comprising in combination side sills provided with bends extending across said entrances and exits, a platform extending from side to side of the car and supported from said sills in a plane entirely below the floor of the car, a single door structure adapted to alternately close or open one or the other of said side entrances, mechanical means supporting said doors when transferring them from one to the other of said openings, a railing separating the entrance and exit passengers from each other, means whereby said railing may be shifted from one side of the car to the other when likewise shifting the entrance to and exits therefrom, two sets of steps between and connecting the platform with the floor on each side thereof, a swinging and a sliding door for each two sets of steps, and means whereby the positions of the adjacent swinging and sliding doors may be reversed with reference to their respective steps to correspond with the shifting of the entrance and exits from one side of the car to the other, substantially as described.
20. A railway passenger car having in combination adjacent inside doors obliquely arranged with reference to the length of the car, a single support common to both of said doors and means whereby one of said doors may be shifted past the other, substantially as described.
25. A railway passenger car having in combination adjacent inside doors obliquely arranged with reference to the length of the car and a single pivoted support common to both of said doors whereby said doors may be shifted respectively from one door opening to that before occupied by the other, substantially as described.
30. A railway passenger car having in combination a car body adjacent inside doors diagonally arranged with reference to each other and the car body, a single support joining said doors at their apex, and means whereby said doors may be simultaneously shifted on said support from one door opening to the other, substantially as described.
35. A railway passenger car having in combination adjacent inside doors diagonally arranged with reference to each other and obliquely arranged with reference to the length of the car, one of which doors slides and the other swings to close and open its doorway, a single support common to both of said doors, means whereby said doors may be shifted from one of the two door openings to the other, and means for limiting the movement of both of said doors in both directions, substantially as described.
40. A railway passenger car having in combination inside doors arranged obliquely with reference to the length of the car, a single support common to both of said doors, and mechanical means operating to simultaneously shift said doors to an operative position relative to either of their door openings, substantially as described.
45. A railway passenger car having in combination adjacent inside doors in oblique arrangement with reference to each other, a single post supporting said doors, means limiting the closing movement of said doors, and a screen outwardly therefrom limiting the opening movement of said doors, substantially as described.
50. A railway passenger car comprising in combination a car floor, a platform extending the entire width of said floor in a plane below the same, steps leading from the platform to the car floor, a door supporting post rising above said platform, in side doors in diagonal arrangement supported from said posts toward their converging point, which doors when closed, have their bottom substantially on a plane with the car floor and when moved to an open
55. A railway passenger car the entrance and exit of which are through the sides of the car at a point substantially removed from its ends, comprising in combination side sills provided with bends extending across said entrances and exits, a platform extending from side to side of the car and supported from said sills in a plane entirely below the floor of the car, a single door structure adapted to alternately close or open one or the other of said side entrances, mechanical means supporting said doors when transferring them from one to the other of said openings, a railing separating the entrance and exit passengers from each other, means whereby said railing may be shifted from one side of the car to the other when likewise shifting the entrance to and exits therefrom, two sets of steps between and connecting the platform with the floor on each side thereof, a swinging and a sliding door for each two sets of steps, and means whereby the positions of the adjacent swinging and sliding doors may be reversed with reference to their respective steps to correspond with the shifting of the entrance and exits from one side of the car to the other, substantially as described.
60. A railway passenger car having in combination adjacent inside doors obliquely arranged with reference to the length of the car, a single support common to both of said doors and means whereby one of said doors may be shifted past the other, substantially as described.
65. A railway passenger car having in combination adjacent inside doors obliquely arranged with reference to the length of the car and a single pivoted support common to both of said doors whereby said doors may be shifted respectively from one door opening to that before occupied by the other, substantially as described.
70. A railway passenger car having in combination adjacent inside doors obliquely arranged with reference to the length of the car and a single pivoted support common to both of said doors whereby said doors may be shifted respectively from one door opening to that before occupied by the other, substantially as described.
75. A railway passenger car having in combination adjacent inside doors obliquely arranged with reference to the length of the car and a single pivoted support common to both of said doors whereby said doors may be shifted respectively from one door opening to that before occupied by the other, substantially as described.
80. A railway passenger car having in combination a car body adjacent inside doors diagonally arranged with reference to each other and the car body, a single support joining said doors at their apex, and means whereby said doors may be simultaneously shifted on said support from one door opening to the other, substantially as described.
85. A railway passenger car having in combination adjacent inside doors diagonally arranged with reference to each other and obliquely arranged with reference to the length of the car, one of which doors slides and the other swings to close and open its doorway, a single support common to both of said doors, means whereby said doors may be shifted from one of the two door openings to the other, and means for limiting the movement of both of said doors in both directions, substantially as described.
90. A railway passenger car having in combination adjacent inside doors diagonally arranged with reference to each other and obliquely arranged with reference to the length of the car, one of which doors slides and the other swings to close and open its doorway, a single support common to both of said doors, means whereby said doors may be shifted from one of the two door openings to the other, and means for limiting the movement of both of said doors in both directions, substantially as described.
95. A railway passenger car having in combination adjacent inside doors diagonally arranged with reference to each other and obliquely arranged with reference to the length of the car, one of which doors slides and the other swings to close and open its doorway, a single support common to both of said doors, means whereby said doors may be shifted from one of the two door openings to the other, and means for limiting the movement of both of said doors in both directions, substantially as described.
100. A railway passenger car having in combination adjacent inside doors diagonally arranged with reference to each other and obliquely arranged with reference to the length of the car, one of which doors slides and the other swings to close and open its doorway, a single support common to both of said doors, means whereby said doors may be shifted from one of the two door openings to the other, and means for limiting the movement of both of said doors in both directions, substantially as described.
105. A railway passenger car having in combination inside doors arranged obliquely with reference to the length of the car, a single support common to both of said doors, and mechanical means operating to simultaneously shift said doors to an operative position relative to either of their door openings, substantially as described.
110. A railway passenger car having in combination adjacent inside doors in oblique arrangement with reference to each other, a single post supporting said doors, means limiting the closing movement of said doors, and a screen outwardly therefrom limiting the opening movement of said doors, substantially as described.
115. A railway passenger car having in combination adjacent inside doors in oblique arrangement with reference to each other, a single post supporting said doors, means limiting the closing movement of said doors, and a screen outwardly therefrom limiting the opening movement of said doors, substantially as described.
120. A railway passenger car comprising in combination a car floor, a platform extending the entire width of said floor in a plane below the same, steps leading from the platform to the car floor, a door supporting post rising above said platform, in side doors in diagonal arrangement supported from said posts toward their converging point, which doors when closed, have their bottom substantially on a plane with the car floor and when moved to an open
125. A railway passenger car comprising in combination a car floor, a platform extending the entire width of said floor in a plane below the same, steps leading from the platform to the car floor, a door supporting post rising above said platform, in side doors in diagonal arrangement supported from said posts toward their converging point, which doors when closed, have their bottom substantially on a plane with the car floor and when moved to an open
130. A railway passenger car comprising in combination a car floor, a platform extending the entire width of said floor in a plane below the same, steps leading from the platform to the car floor, a door supporting post rising above said platform, in side doors in diagonal arrangement supported from said posts toward their converging point, which doors when closed, have their bottom substantially on a plane with the car floor and when moved to an open

position project over the platform, substantially as described.

19. A railway passenger car having in combination inside doors which in their closed position form two sides of a triangle, a single post supporting said doors at the apex of said triangle, a similarly arranged fixed screen outwardly from said doors, the apex of which screen is in the same line as that of the doors, and means whereby said screen limits the opening movement of both of said doors, substantially as described.

20. A railway passenger car comprising in combination a car body provided with entrances thereto, a single door structure for closing one side only of said car, means for suspending said doors whereby said doors may be transported in a direct line from

one side of the car to the other for alternately closing and unclosing the openings therein, substantially as described.

21. A side entrance car comprising in combination a single door structure, an elevated track extending transversely across the said car in a plane directly above said openings and forming a tramway for shifting said door structure from one side entrance opening to the other, substantially as described.

In witness whereof, I have hereunto set my hand and affixed my seal, this 31st day of July, A. D. 1912.

HERBERT McNULTA. [L. S.]
